UNITED STATES PATENT OFFICE.

GEORGE D. GREEN, OF ROCHESTER, NEW YORK, ASSIGNOR TO JAMES H. SAGER, OF SAME PLACE.

DESIGN FOR A REAR TRIANGLE FOR CYCLE-FRAMES.

SPECIFICATION forming part of Design No. 34,579, dated May 28, 1901.

Application filed April 15, 1901. Serial No. 56,020. Term of patent 14 years.

To all whom it may concern:

Be it known that I, GEORGE D. GREEN, a citizen of the United States, and a resident of Rochester, in the county of Monroe and State 5 of New York, have invented and produced a certain new and original Design for the Rear Triangle of Cycle-Frames, of which the following is a specification.

My invention relates to a design for the rear triangle of cycle-frames.

The drawing is a perspective view of such rear triangle, showing my new design.

As shown in the drawing, the features of my design are the straight tube A, that extends upwardly from the crank-hanger E and 15 is joined at its upper end at an acute angle

to the two straight tubes B B, which latter are spread apart at their lower ends and there connected, respectively, at the points b b with the ends of the lower parallel side tubes C C, 20 which extend downwardly from said points b b and then curve upwardly in similar curves c c.

The leading feature of my design is the downward curvature c in the side tubes of the rear triangle of a cycle, as shown. 25

I claim—

The design for a rear triangle of cycle-frames, substantially as shown and described.

GEO. D. GREEN.
